UNITED STATES PATENT OFFICE.

WILLIAM HARTZELL, OF PHILADELPHIA, PENNSYLVANIA.

TIME-DAMPER MECHANISM.

SPECIFICATION forming part of Letters Patent No. 754,446, dated March 15, 1904.

Application filed November 19, 1903. Serial No. 181,816. (No model.)

To all whom it may concern:

Be it known that I, WILLIAM HARTZELL, a citizen of the United States, residing at Philadelphia, in the county of Philadelphia, State of Pennsylvania, have invented certain new and useful Improvements in Time-Damper Mechanism, of which the following is a specification, reference being had to the accompanying drawings, forming part hereof.

10 The object of the present invention is to provide novel mechanism which can be set for automatically operating at predetermined periods the lids and dampers of a stove, range, or other suitable heater.

15 The invention consists of the improvements hereinafter described and finally claimed.

The nature, characteristic features, and scope of the invention will be more fully understood from the following description, taken 20 in connection with the accompanying drawings, forming part hereof, and in which—

Figure I is a front elevational view of a range or stove, showing in application thereto the time-damper mechanism of the invention. 25 Fig. II is a detached side elevational view of a portion of the mechanism. Fig. III is a sectional view taken on the line 3 3 of Fig. II. Fig. IV is a sectional view taken on a line 4 4 of Fig. III, and Fig. V is a modified form of 30 the device.

Referring to the drawings, *a* represents a stove or range, with its complemental fire-chamber *b* and ash-pit *b'*.

c is an auxiliary plate adapted to be fitted to 35 the openings ordinarily occupied by the lids of a stove or range. As shown in Fig. III, this auxiliary lid consists of two members, one of which is rotatable, having openings adapted to register with each other. Formed integral 40 with the base of this lid is a socket *e*, adapted to receive a bracket *f*. Fulcrumed to the bracket *f* is an arm *g*, having depending therefrom a projection *g'*. Having pivotal engagement therewith is a bifurcated finger *g''*, adapted 45 to engage a pin *d*, projecting from the upper member of the auxiliary lid. Pivoted to one end of the arm *g* is a forked rod *h*, whose function will appear hereinafter. The opposite end of the arm *g* is under spring tension, 50 as at *i*. If desired, a weight may be employed

to cause the arm *g* to drop by gravity. Detachably attached to the bracket is a time-piece, as an alarm-clock, provided with the usual alarm-winding stem *j*. Adapted to rest upon this stem is a ring or hook, which is attached to a chain or flexible connection *k*, which in turn is connected with the arm *g*, as shown. Referring to the ash-pit *b'*, the same is closed by the ordinary hinged door and its complemental damper. The pin or knob *l* of the said damper has secured to it springs *l'* and *l''*, the former terminating in a hook adapted normally to engage a pin *l'''* and the latter being secured as at *l''*. The forked portion of the rod *h* engages the part *l'*, for a purpose 65 to be presently described.

As is well known, when banking a fire for the night the damper in the ash-pit is closed and a lid of the stove or range is removed or partially set aside or the trap-door opened. 70 In the morning the damper is opened, the lid returned to its proper place, or the trap closed, with the result that the fire burns up prior to throwing on a fresh supply of coal. By the present invention it is calculated to 75 cause the fire to burn up in the morning by automatic means in the following manner, to wit: The alarm is set at the desired time, and the auxiliary plate, together with its bracket, having taken the place of the ordinary lid of 80 the stove or range, the clock is suspended in the manner described and the flexible member *k* placed over the projection *j* and the forked member placed in engagement with the part *l'* on the damper. The rotatable member of the auxiliary lid *c* is then adjusted by 85 hand for admitting the proper amount of air, this being facilitated by the rotation of the pin *d* and the bifurcated member *g''*. In the morning the alarm releases the stem *j* and the 90 flexible member *k*, whereupon the spring-controlled arm *g* shifts the member *g''*, thus causing the closing of the auxiliary plate and forcing downward the rod *h*, which releases the spring *l'* and causes the damper to open. When 95 the fire has burned up sufficiently, the device may obviously be detached from the stove or range, the clock used for ordinary purposes, and the rest of the apparatus set to one side.

In the modification shown in Fig. V the 100

auxiliary plate consists of a base having a hinged member adapted to be left for the night in the position shown in the figure. In the morning when the alarm goes off the flexible member *h* is released, the plate falls by gravity, the rod *h* is pushed downward, and the damper opened, as hereinbefore described.

It will be obvious to those skilled in the art to which the invention appertains that modifications may be made in detail without departing from the spirit thereof. Hence I wish it understood that I do not limit myself to the precise construction and arrangement of parts herein shown and described; but,

Having thus described the nature and objects of the invention, what I claim as new, and desire to secure by Letters Patent, is—

1. The combination with a stove or range of an auxiliary plate or lid provided with openings adapted to register with each other, a supporting device carried thereby and having fulcrumed therewith a spring-controlled arm, a member for shifting the plate operated thereby, a spring-operated damper, a clock mechanism, suspended from said supporting device and means for releasing the arm and damper, substantially as described.

2. The combination with a stove or range of an auxiliary plate or lid having openings for registering with each other, a supporting

device carried thereby, a spring-operated damper, a clock mechanism, a spring-controlled arm having a projection, a member for shifting the plate attached thereto, a rod between the arm and the damper and a flexible member carried by the arm and adapted to be released by the clock mechanism, substantially as described.

3. The combination with a stove or range of a two-part auxiliary plate or lid having openings adapted to register with each other, one of which parts being provided with a pin, and a supporting device carried by the other of said parts, a spring-controlled arm, fulcrumed to said support and adapted to shift a forked member having engagement with the said pin, a spring-controlled damper, a rod connected with the arm and adapted to release the said spring, a clock mechanism suspended from the support and a flexible member adapted to be released by the winding-stem of the clock to operate the arm, substantially as described.

In testimony whereof I have hereto set my hand and seal.

WILLIAM HARTZELL. [L. S.]
